UNITED STATES PATENT OFFICE

JEROME EDSON ANDREWS, OF ANDOVER, MASSACHUSETTS

DESIGN FOR A SHOE

Application filed November 10, 1932. Serial No. 45,864. Term of patent 3½ years.

To all whom it may concern:

Be it known that I, JEROME EDSON ANDREWS, a citizen of the United States, residing at Andover, in the county of Essex and State of Massachusetts, have invented a new, original, and ornamental Design for a Shoe, of which the following is a specification, reference being had to the accompanying drawing, forming part thereof, in which—

Fig. 1 is a view in side elevation, and Fig. 2 is a plan view of a shoe showing my new design:

An essential feature of my design resides in the ornamental effect produced by the double rows of perforations in the quarter and vamp in contrast with the portions of the shoe shown in dark color.

I claim:

The ornamental design for a shoe, as shown and described.

In testimony whereof, I have signed my name to this specification.

JEROME EDSON ANDREWS.
